UNITED STATES PATENT OFFICE.

FRANK F. SCHWALLER, OF ST. LOUIS, MISSOURI.

BEDSTEAD-CANOPY.

983,407.

Specification of Letters Patent.

Patented Feb. 7, 1911.

Application filed June 22, 1910. Serial No. 568,326.

To all whom it may concern:

Be it known that I, FRANK F. SCHWALLER, a citizen of the United States, residing at St. Louis, State of Missouri, have invented certain new and useful Improvements in Bedstead-Canopies, of which the following is a full, clear, and exact description, reference being had to the accompanying drawings, forming a part hereof.

10 My invention has relation to improvements in bed-stead canopies; and it consists in the novel details of construction more fully set forth in the specification and pointed out in the claim.

15 In the drawings, Figure 1 is a side elevation of a conventional metallic bed-stead showing my invention in position; Fig. 2 is a top plan of Fig. 1 (the bed slats being omitted); Fig. 3 is an end view of the head 20 and foot sections of the bed, with the folded canopy between them in position for packing and shipment; Fig. 4 is a front elevation of the canopy broken at the middle and at the end near the bed post showing 25 its normal position, and showing by dotted lines the manner of folding the sides of the canopy to bring the same into position for packing; Fig. 5 is an inside view of one side of the canopy, the lower portion and the 30 upper pipe members being broken off; Fig. 6 is a cross-section on the line 6—6 of Fig. 5; and Fig. 7 is a cross-section on line 7—7 of Fig. 5.

35 The object of my invention is to construct a canopy for iron bed-steeds which may be detached and folded in compact relation to the head section of the bed and the foot section usually packed therewith for purposes of shipment.

40 By the use of the improved canopy, the parts referred to may be packed in close and compact relation thereby reducing the shipping space required therefor, all as will fully appear from a detailed description of 45 the invention which is as follows:

Referring to the drawings, 1, 1, are the corner posts of the head section of an ordinary and conventional iron bed-stead, and 50 1', 1', the corresponding posts of the foot section. The canopy herein comprises a pair of parallel members *a*, *b* made of piping, the members terminating respectively in parallel arms *a'*, *b'* disposed lengthwise of the bed-stead. The terminals of the arms 55 *a'* are provided with fittings 2, 2, which

are passed over the screw-stems 3, 3, terminating the posts 1, 1, and are clamped to said posts by the ornamental knobs 4, 4 which are provided with screw-sockets passed over the screws 3, 3, and driven home 60 tightly against the fittings 2, 2. The members *a*, *b* and their arms *a'*, *b'* are connected by spacing pieces 5, of any approved design, the arms *b'* being shorter than the arms *a'* and terminating a suitable distance 65 from the posts 1, 1, when the canopy is in position on the bed-stead. The depending sides of the canopy are in the form of an ornamental frame, comprising in the present design a front arm *d* the upper free end 70 of which terminates in a ring or loop 6 loosely encompassing the arm *b'*, the ring 6 being provided with an elongated slot 7 through which passes a screw or pin 8 carried by the arm *b'* this arrangement allowing the side frame to oscillate freely about the arm *b'*. The side frame comprises in addition to the arm *d*, an arm *e* whose upper end is pivotally suspended from a screw stud 8' at the end of the arm *b'*. The side 75 frame further comprises a horizontal arm *h*, the rear free end of which terminates in a transverse fork 9 which is rounded to conform to the cylindrical curvature of the post 1, the arm *h* serving the purpose of a 80 brace to hold the canopy in position against the head section of the bed-stead. It will thus be seen that the side frames (composed of the members *d*, *e*, *h*) are pivotally suspended from, or in hinged relation to the 85 member *b* (or rather the arms *b'* thereof). When therefore the canopy is removed from the bed-stead (by first unscrewing the knobs 4 and lifting the fittings 2 out from the screws 3) the side frames (*d*, *e*, *h*) are 90 folded about the arms *b'* into substantial parallelism with the members *a*, *b*, and the canopy thus folded is placed against the head-section of the bed-stead (after the sides of the bed-stead have of course been 95 detached), then the foot section is moved up against the canopy (Fig. 3) making a compact package for shipping purposes.

Having described my invention what I claim is—

105 In combination with the side posts of the head section of a bed-stead, a canopy comprising a pair of parallel members terminating in side parallel arms, the arms of the lower member being shorter than the 110

arms of the upper member, and the ends of the arms of the upper member being detachably secured to the upper ends of the posts, side frames depending pivotally from 5 the arms of the lower transverse member and comprising suitable members hinged to said arms, and a bottom member or brace terminating in a fork engaging the adjacent post of the head section of the bed-

stead, the parts operating substantially as, 10 and for the purpose set forth.

In testimony whereof I affix my signature, in presence of two witnesses.

FRANK F. SCHWALLER.
